UNITED STATES PATENT OFFICE.

JAMES F. MOLLOY, OF WEST HAVEN, CONNECTICUT.

CAST-OFF.

No. 908,480.

Specification of Letters Patent.

Patented Jan. 5, 1909.

Application filed June 4, 1908. Serial No. 436,638.

To all whom it may concern:

Be it known that I, JAMES F. MOLLOY, a citizen of the United States, residing at West Haven, in the county of New Haven, and State of Connecticut, have invented a new and useful Improvement in Cast-Offs; and I do hereby declare the following, when taken in connection with the accompanying drawings and the letters of reference marked thereon, to be a full, clear, and exact description of the same, and which said drawings constitute part of this specification, and represent, in—

Figure 1 a front view of a cast-off constructed in accordance with my invention. Fig. 2 a rear view of the same. Fig. 3 a vertical sectional view. Fig. 4 a rear view of the upper portion of the front member, detached. Fig. 5 a view in rear elevation 20 of the upper end of the rear member, detached. Fig. 6 a view in elevation of the spring detached. Fig. 7 a front view of a modified form of cast-off.

This invention relates to an improvement 25 in cast-offs, and while particularly adapted for suspenders, is applicable for other purposes, such, for instance, as check reins for harnesses. In the usual construction of these devices a loop is employed to which 30 the parts of a cast-off are hinged, and it is desirable that one member shall have a tongue adapted to bear against a spring on the other part so that the members will be locked in their closed position; and in order to provide 35 for this spring engagement and suitably support the members on the loop, they must be so wide as to be unsightly.

The object of this invention is to so form 40 the members that one will ride over the other whereby they may be made comparatively narrow; and the invention consists in the construction hereinafter described and particularly recited in the claims.

In illustrating my invention I have shown 45 a cast-off particularly adapted for suspenders, and this description will be sufficient to enable others to adapt it for various purposes.

As shown, I employ a loop 2 preferably 50 formed from wire and having the central portion 3 of the lower bar 4 slightly offset. The upper end of the rear member 5 is rolled to form a sleeve 6 which surrounds the central portion of the lower bar 4; and secured 55 to this member is a spring 7 the upper end

8 of which projects above the top of the sleeve. This spring may be secured to the rear member by forming the rear member with fingers 9 and the spring with notches 10 through which the fingers extend, the 60 fingers being turned down over the face of the spring as shown in Fig. 2 of the drawings.

The front member 11 is formed at its upper edge with ears 12 at opposite sides, and these ears are turned over the central portion 3 of the lower bar at opposite ends of the sleeve 6; while the central portion of the member 11 is formed with a rearwardly extending tongue 13 which is adapted to pass over and ride upon the sleeve 6 and to engage with the upper end of the spring 7. The lower end of the rear member may be formed with a curved hook 14, and the front member with a corresponding curved face 15 adapted to close the hook, and terminating 75 in a thumb-piece 16, this frame being particularly adapted for round suspender ends, or its ears may be adapted to engage and support a runner 17, as shown in Fig. 7 of the drawings. The hook 14 will be open for 80 the entrance or removal of the suspender end or other attachment, and the end of the tongue 13 engaging with the spring 7 locks this member in either its open or closed position, and by extending over the sleeve 6 provides 85 suitable bearing for the front member without making the parts so wide as to provide for a direct bearing of the central part of the front member upon the lower bar 4.

I claim:—

1. A cast-off comprising a loop, a rear member formed with a centrally arranged sleeve surrounding one pair of said loop, a spring attached to the rear member and extending above said sleeve, combined with a 95 front member formed on opposite sides with ears which surround the bar of the loop at opposite ends of the said sleeve, and with a centrally arranged tongue extending rearward over said sleeve and into engagement with the upper end of said spring, substantially as described.

2. A cast-off comprising a loop having its lower bar offset, a rear member provided at its upper end with a sleeve surrounding the central portion of said lower bar, a spring attached to the rear member and extending above said sleeve, a front member formed on opposite sides of its upper edge with ears which are turned around the lower bar of the 110

loop on opposite sides of said sleeve, said front member formed at its upper end with a rearwardly extending tongue which extends over and bears upon said sleeve, said members adapted at their lower ends to engage the device to which it is to be attached, substantially as described.

In testimony whereof, I have signed this specification in the presence of two subscribing witnesses.

JAMES F. MOLLOY.
